UNITED STATES PATENT OFFICE.

ALBERT A. PAULY, OF YOUNGSTOWN, OHIO.

CONCRETE-CONSTRUCTING MACHINE.

No. 829,227.

Specification of Letters Patent.

Patented Aug. 21, 1906.

Application filed October 26, 1905. Serial No. 284,587.

To all whom it may concern:

Be it known that I, ALBERT A. PAULY, a citizen of the United States of America, residing at Youngstown, in the county of Mahoning and State of Ohio, have invented certain new and useful Improvements in Concrete-Constructing Machines, of which the following is a specification, reference being had therein to the accompanying drawings.

This invention relates to certain new and useful improvements in concrete-constructing machines; and the primary object of this invention is to provide a portable machine that can be easily and quickly manipulated to construct a concrete wall, foundation, pier, abutment, or the like.

Another object of this invention is to provide a machine of the above type that will be strong and durable, comparatively inexpensive to manufacture, and highly efficient for the purposes for which it is intended.

Briefly described, my improved machine comprises a base upon which is slidably mounted an angular frame, and in said frame is journaled a plurality of shafts, over which chains pass to support retaining-boards, said boards being employed to form a mold or form for a foundation or wall to be constructed. In connection with the machine I use other boards for retaining-boards, which may be positioned at an angle to the first-named boards, in order that an angle in the wall or foundation can be readily constructed.

The above construction, together with the details of the invention, will be hereinafter more fully described and then specifically pointed out in the claims, and, referring to the drawings accompanying this application, like numerals of reference designate corresponding parts throughout the several views, in which—

Figure 1 is a side elevation of my improved machine. Fig. 2 is a plan. Fig. 3 is a rear elevation. Fig. 4 is a perspective view of one of the braces.

To put my invention into practice, I employ a base 1, the central portion of which is cut away, as indicated at 2. Upon the base 1 I adjustably secure, by suitable brackets 3 3, a substantially rectangular frame 4, carrying upon its front edge standards 5, the upper ends of which are provided with a cross-head 6, to which are connected rearwardly-extending bars 7 7, said bars being fixed to the frame 4, as at 8 8, and serving to brace the

standards 5 5. The front edge of the rectangular frame 4 is provided with two links 9 9, said links being connected to levers 10 10, carried by the ends of a pivotally-mounted transverse shaft 11, said shaft being mounted upon the base-plate 1. By operating the levers 10 10 the rectangular frame, together with the standards 5 5 and their appurtenant parts, can be moved rearwardly. The cross-head 6 is further braced by rearwardly-extending inclined rods 12 12, said rods being secured to the frame 4, as at 14 14. The standards are braced by tie-rods 15 15 and 16 16, which are connected to the sides of the rectangular frame, as at 17 17. Said tie-rods are provided with turn-buckles 18 18, in order that the standards 5 may be adjusted relatively to the rectangular frame 4. The bars 7 7 are provided with sleeves 19 19 and 20 20. In the sleeves 19 is journaled a shaft 21, while in the sleeves 20 is journaled a shaft 22. Said shafts are provided with crank-handles 23 23, a crank-handle being placed upon each side of the machine, whereby the shafts can be easily rotated.

The cross-head 6 is provided with two T connections 24 24, and extending through said connections are angularly-disposed bars 25 25, said bars protruding over the front edge of the machine, as clearly illustrated in Figs. 1 and 2 of the drawings. Mounted in the outer ends of the bars 25 25 is a transverse bar 26. Connected to the shaft 21, as at 27 27, are chains 28 28, which pass over the transverse bar 26 and support a retaining-board 29, said board being parallel with the front side of the machine.

Secured to the shaft 22, as at 30 30, are chains 31 31, said chains passing over the cross-head 6 of the standards 5 and supporting a retaining-board 32 adjacent to the standards 5 5, the board 32 and the board 29 being in horizontal alinement with one another and forming a trough in which concrete is to be placed to construct the wall.

In conjunction with the machine just described I employ end boards 33 33, said boards being retained upon each side of the machine by telescopic braces 34 34, which are connected to the rear face of the end boards, as at 35' 35', and to the central standard 5, as clearly illustrated in Fig. 3 of the drawings. The boards 33 33 constitute inner retaining-boards, and in connection with these boards I employ outer retaining-boards

35 35, said boards being suspended upon chains 36 36, that pass over outriggers 37 37, carried by posts 38 38, located upon the base 1. The chains 36 36 can be manipulated by 5 hand or may be connected to one of the shafts 21 or 22 in order to elevate the outer retaining-boards 35.

The boards 29 are connected with the boards 32, and the boards 35 are connected o with the boards 33 by braces at the tops of the boards and bolts at the bottoms of the same, as illustrated in the drawings, the braces being designated 29' and the bolts 33'.

We will assume that the machine is to be 15 used to build a concrete foundation and that the proper position of the foundation has been determined. The machine is moved adjacent to the predetermined position of the wall and the retaining-boards 32 and 29 20 placed whereby they will form a trough to receive the concrete. After the concrete has been tamped in position the retaining-boards 32 and 29 are elevated by the chains 28 and 31 through the medium of the shafts 21 and 25 22. The boards are elevated to the top edge of the tamped concrete and are in position to receive concrete to form a top layer upon the first-laid concrete. This operation is continued until the foundation of a desired height 30 is obtained. During the formation of the concrete between the retaining-boards 32 and 29 the machine can be adjusted by the levers 10 10—that is, the framework of the machine can be moved relatively to the base of 35 the machine, and in this manner the retaining-board 32 can be withdrawn from the formed concrete.

The inner and outer retaining-boards 35 and 33 are used in connection with the retaining-boards 29 and 32 when an angle in a foundation is to be formed, these boards being positioned at any desired angle to the retaining-boards 29 and 32.

I preferably construct the machine of sections of pipe or tubing which are joined together to produce a metallic framework capable of being adjusted to move as a wall is constructed. It is essential in the manufacture of machines of this type that material be em-

ployed capable of withstanding the rough 50 usage to which the machines are subjected. Consequently I have employed metallic pipes or tubing of a strong and durable nature which will form a framework that can be readily adjusted and transported at any time 55 desired.

By referring to Fig. 1 of the drawings it will be observed that the base-plate 1 of my improved machine is mounted upon rollers, whereby the machine can be easily and 60 quickly moved from place to place as a foundation-wall or the like structure is built.

Such changes in the construction and operation of the machine as are permissible by the appended claims may be resorted to without departing from the spirit and scope of the invention.

What I claim, and desire to secure by Letters Patent, is—

1. In a machine, the combination with a 70 base-plate, of a rectangular frame adjustably mounted upon said plate, standards carried by said frame, brace-rods connecting said standards and said frame, revoluble shafts carried by said brace-rods, a cross-head carried by said standards, a bar supported by said cross-head, chains connected with said shaft and extending over said cross-head and said bar, retaining-boards supported by said chains, retaining-boards supported 80 by said standards, retaining-boards adjustably mounted upon posts, substantially as described.

2. In a machine, the combination of a base-plate, standards adjustably mounted upon 85 said base-plate, a cross-head carried by said standards, a bar supported by said cross-head, retaining-boards suspended from said cross-head and said bar, other retaining-boards mounted adjacent to said base-plate, 90 means to adjust said retaining-boards, substantially as described.

In testimony whereof I affix my signature in the presence of two witnesses.

ALBERT A. PAULY.
